PANTY GIRDLE

Doris M. Brown, Dover, Del., assignor to Sarong, Inc.,
Dover, Del., a corporation of Delaware

Filed Dec. 30, 1965, Ser. No. 400

Term of patent 14 years

(Cl. D2—4)

FIG. 1

FIG. 1 is a front elevational view of a girdle, showing my new design;

FIG. 2 is a back elevational view thereof; and

FIG. 3 is a front perspective view.

The dominant feature of my girdle design resides in an overlapped crotch that has an overlapping exposed free edge that is off-center and that extends from the front seam of one side panel to the back seam of the same side panel, substantially as shown.

I claim:

The ornamental design for a panty girdle, substantially as shown and described.
